US00D997938S

(12) **United States Design Patent** (10) **Patent No.:** **US D997,938 S**
(45) **Date of Patent:** **** Sep. 5, 2023**

(54) **HEALTH MONITOR DEVICE WITH SENSORS**

(71) Applicant: **Analog Devices, Inc.**, Wilmington, MA (US)

(72) Inventors: **Tony J. Akl**, Bedford, MA (US); **Venugopal Gopinathan**, Boston, MA (US); **Sriram Ganesan**, Bangalore (IN); **Abigail Reynolds**, Medford, MA (US)

(73) Assignee: **Analog Devices, Inc.**, Norwood, MA (US)

(**) Term: **15 Years**

(21) Appl. No.: **29/724,975**

(22) Filed: **Feb. 20, 2020**

(51) LOC (14) Cl. **24-02**

CLAIM

The ornamental design for a health monitor device with sensors, as shown and described.

DESCRIPTION

A portion of the disclosure of this patent document contains material which is subject to copyright protection. The copyright owner has no objection to the facsimile reproduction by anyone of the patent disclosure or the patent disclosure, as it appears in the Patent and Trademark Office patent file or records, but otherwise reserves all copyright rights whatsoever.

FIG. 1 is a front view of a health monitor device with sensors;

FIG. 2 is a front perspective view thereof;

FIG. 3 is a back view thereof; and,

FIG. 4 is a back perspective view thereof.

The dot-dash broken lines illustrate portions of the health monitor device with sensors that form no part of the claimed design.

1 Claim, 4 Drawing Sheets
